Norman G. Patterson
ATTORNEY

UNITED STATES PATENT OFFICE.

THOMAS F. WILLIAMS, OF KEYPORT, NEW JERSEY, ASSIGNOR TO INGLIS M. UPPERCU,
OF DEAL, NEW JERSEY.

OIL BURNER.

Application filed September 30, 1925. Serial No. 59,707.

This invention relates to oil burners, and the embodiment as herein disclosed features an improved and novel burner especially adapted for the heating of dwellings etc.

5 The chief object of this invention is to provide a burner of the kind described that is entirely automatic and positive in its operation.

A further object of this invention is to 10 provide an improved burner that is simple in form and operation and that when the same has been installed, practically takes care of itself for indefinite periods and automatically maintains a predetermined degree 15 of temperature within the dwelling irrespective of climatic changes.

A still further object of the invention is to provide a burner having novel and improved features and that can be manufactured and efficiently operated at a low cost. 20

Some of the essential features of the burner might be enumerated as follows: The fuel is converted into vapor and premixed with air in correctly controlled quantities. 25

Vaporization is due to reflected heat upon the surface of the oil which burns in the form of gas at the outlet of the burner, there being no flame at or near the surface of the oil. 30

Further objects and advantages of the invention will be in part apparent from an inspection of the accompanying drawings and in part will be more fully set forth in the following particular description of one 35 form embodying my invention, and the invention also consists in certain new and novel features of construction and combinations of parts hereinafter set forth and claimed.

In the drawings:-

40 Figure 1 is a vertical section of the present invention.

Figure 2 is an elevation of a portion of the invention not included in the showing of Fig. 1.

45 Figure 3 is an alternative structure of that shown in Fig. 2.

In the present instance 10 designates the lower or bowl portion of the burner which is formed so as to provide an annular caved channel 11 in which the oil 12 is retained. To the bowl 10 there is attached in a removable manner, an upper portion 9 which is somewhat constricted towards its axis and adapted to support a further 50 portion 15 preferably constructed of re-

fractory material and constricted to a greater degree at 16 so as to form in conjunction with the portion 9, a mixing chamber 43 having a relatively narrow axial passage due to the constriction at 16. The annular formation 60 of the bowl 10 provides a central passage or air conductor 13 having an aperture above the high level of the fuel 12. This air conductor connects with an air chamber or base 14, and a heat deflector 17, also preferably 65 formed of refractory material, is mounted above the air conductor 13 upon a pin 18 secured in a web 19.

It will be understood that due to the annular formation of the bowl 10, the surface 70 area of the fuel contained therein can be increased or decreased by raising or lowering the level of the fuel, and in consequence thereof, the surface of the fuel which is exposed to the reflected heat will generate more 75 or less vapor dependent on its greater or lesser area. Accordingly the amount of heat generated by the burner will depend upon the height at which the fuel is maintained in the bowl 10. 80

The fuel is conducted from a source of supply (not shown) to a control mechanism 20 by means of an opening 21 therein, and thence to the bowl 10 of the burner by means of the pipe 22. This control mechanism is 85 adapted to be pre-set so as to limit the thermal output of the burner to any predetermined maximum suitable to meet the requirements of any particular installation. In other words, the device is set in a manner 90 to be hereinafter described, so as to provide heat sufficient for either a small or large building. 80

Within a float chamber 23 there is supported for vertical movement in either direction a float cage 24, which is raised or lowered by a rod 25 and a manually operable lever 26. To the lower portion of the cage 24 there is connected a tube 27 which enters an auxiliary chamber 28 and openings 29 100 are formed in the cage adjacent to the upper end of the tube 27. Within the cage there is supported a float 31 which is operated in a conventional manner so as to open or close a needle valve 32. 105

In some convenient position in the pipe 22, there is inserted a valve 33 which is operated by a solenoid 34 and an auto transformer 34, which are controlled by a thermostat 35 that is responsive to changes in 110

temperature and which operates within certain preset limits so as to open or close the circuit 36. A screw 37 is provided by which an adjustment can be made so that the 5 valve will always bypass a minimum amount of fuel to the burner or sufficient to fill a recess 40 in the lower portion of the bowl and thus maintain therein a pilot light to insure constant operation of the burner under 10 any and all changes of temperature.

A fan blower 42 having a driving connection with a motor 42^a provides a forced draught of air to the mixing chamber 43 by the medium of a pipe 44 which enters 15 the base 14, and a relatively large diameter tube 45 is also provided by means of which a natural flow of air may be maintained when for any reason the blower ceases in its operation. The tube 45 is provided with a 20 shutter 46 which normally remains closed during the operation of the blower so as to prevent the forced flow of air from passing out through the relatively large diameter tube instead of entering the burner, it being 25 understood that both the pipe 44 and the tube 45 have connection with the base 14. The shutter 46 is operated by a solenoid 49 and an auto transformer 49^a which are also controlled by the thermostat 35.

30 With reference to Fig. 3 there is shown an alternative structure in which the tube 45 is connected directly to the blower 42, the smaller pipe 44 being eliminated. With the particular construction as shown in Fig. 35 a natural flow of air can be conveyed to the burner by means of the same tube, an entrance for the air being provided in this instance by the opening 50 in the side of the blower.

40 The lower portion of the burner is connected by means of a pipe 52 to a suitable receptacle 53 into which the oil sludge is drained by gravity.

45 A small priming cup 54 is connected to the burner by means of a pipe 55.

The operation of the burner is as follows:

50 A quantity of fuel is permitted to flow into the burner and a few drops of gasoline from the cup 54 added thereto for purposes of ignition. When sufficient heat has been generated by the direct burning of the oil to effectively heat both the deflector 17 and the upper portion 15 of the burner, the reflected heat upon the surface of the oil will 55 cause a vapor to arise therefrom which will rapidly increase in volume as the heat deflecting portions becomes more and more heated. By the admixture of air with this vapor, (the direction of air currents being

60 across the arising vapor and as indicated by the arrows in the drawings) a gas will be formed that burns above the constricted portion 16 of the burner. The float chamber 24 is set by means of the lever 26 to some intermediate position and as the oil flows

into the chamber 28 it will rise through the tube 27 into the float cage 24 and out of the openings 29 into the float chamber 23. As the oil rises in the main chamber, it also finds its level in the bowl of the burner, and 70 will continue to rise until it has reached approximately the center line of the float cage 24 when the float 31 will close the valve 32 and prevent further flow of oil for a short period or until some of the oil in the bowl 75 has been consumed. As has been said hereinbefore, the setting of the float cage 24 determines the maximum output of the burner for that particular installation.

It is assumed that during the above described operation of starting the burner, that the room temperature is below normal or below that at which the thermostat 35 has been set to function. In consequence thereof the thermostat will be in its closed position 80 as shown, thus permitting the current to flow to the motor 42^a so as to drive the blower 42 and create a forced draught. The flow of the current through the circuit 36 also reacts on the solenoids 34 and 49 and 85 their associated auto transformers thus maintaining the shutter 46 in a closed position and the valve 33 in a fully opened position. The valve 33 will thus permit the oil to flow through the pipe 22 to the burner until 90 it reaches the height at which the control mechanism 20 is set.

When the room temperature rises to a degree corresponding with the setting of the thermostat 35, the thermostat will open the 100 circuit 36 and, as a result thereof the blower will cease to operate; the shutter 46 will open and permit a natural flow of air through the tube 45 and the valve 33 will close to the extent allowed by the screw 37 105 thus permitting only a certain amount of fuel to pass into the burner. If under these conditions enough heat is generated to maintain the desired temperature within the dwelling, the exterior temperature being a 110 factor in the maintenance of the same, the burner will continue to operate under a natural draught. Should the room temperature drop however at anytime to a point below the present limit, the circuit will again be 115 closed, the blower set into operation again, the shutter 46 closed and the valve 33 opened, thus immediately increasing the thermal output of the burner. The above described operation will continue in cycles, the duration 120 of each cycle being dependent upon exterior climatic conditions, or upon the extent to which the exterior air is permitted to enter the building.

Should the flow of electrical current in the 125 main line cease for any length of time due to a break in the line or other causes, the blower will cease to function and the burner will operate on natural draught as the shutter 46 will be opened simultaneously with the stop- 130

ping of the blower. Under such conditions the adjusting screw 37 should be set so as to open the valve 33 to a greater extent until such a time when the flow of current is resumed.

It will be seen that the operation of the burner is entirely automatic, self controlled and constant in the production of heat, that it is responsive to any fluctuations in the weather and that it is not dependent entirely as to its efficient operation upon the continuity of the electrical energy in the circuit.

Attention is directed to the fact that the upper portion 15 of the burner and the deflector 17 with the construction as shown, can readily be removed for cleaning purposes.

It should be understood that the embodiment as described is preferably used in conjunction with a suitable heat distributing device such as a steam boiler or furnace.

While I have shown and described and have pointed out in the annexed claims certain novel features of my invention, it will be understood that various omissions, substitutions and changes in form and detail of the device illustrated and in its operation may be made by those skilled in the art without departing from the spirit of the invention.

Having thus described my invention, I claim—

1. A burner of the class described, comprising in combination a bowl adapted to contain a variable quantity of liquid fuel said bowl being so formed that the surface area of the fuel contained therein will be increased or decreased in accordance with the quantity of fuel, a member removably mounted upon said bowl said member providing a mixing chamber above the bowl, an element mounted upon said member and of

relatively smaller inside diameter intermediate its ends so as to provide a constricted axial passage over said mixing chamber, an air conductor extending centrally through the bowl with an aperture disposed above the fuel level, and a deflector disposed above said air conductor and extending through said axial passage.

2. In a liquid fuel burner, the combination of a bowl providing an annular concaved channel adapted to contain a quantity of liquid fuel and so formed as to provide a centrally disposed air conductor which extends above the level of the fuel, a pair of members removably mounted upon said bowl said members so formed as to provide a mixing chamber and an axial passage of relatively smaller diameter, and a deflector disposed over said air conductor and extending through said axial passage, and means adapted to conduct the fuel to the bowl.

3. In apparatus of the class described, the combination of a bowl adapted to contain a quantity of liquid fuel said bowl being so formed that the surface area of the fuel contained therein can be increased or decreased, a means removably mounted on said bowl to form a mixing chamber said means having a constricted portion providing a relatively narrow axial passage, an air conductor extending centrally through said bowl and provided with an aperture disposed above the level of the fuel, a deflector disposed above said air conductor, a conduit adapted to convey the fuel to the bowl, and means having connection with said conduit and adapted to maintain the fuel in the bowl at a predetermined height.

Signed at Keyport, in the county of Monmouth and State of New Jersey, this 22nd day of September A. D. 1925.

THOMAS F. WILLIAMS.
